UNITED STATES PATENT AND TRADEMARK OFFICE
CERTIFICATE OF CORRECTION

PATENT NO. : Des. 503,822 S
APPLICATION NO. : 29/192029
DATED : April 5, 2005
INVENTOR(S) : Tim Monroe

Page 1 of 7

It is certified that error appears in the above-identified patent and that said Letters Patent is hereby corrected as shown below:

The Title Page, showing an illustrative figure, should be deleted and substitute therefor the attached title page.

Delete drawings sheets 1-4 and 8 and substitute therefor the drawing sheets, consisting of figs. 1-4 and 8 as shown on the attached pages.

Signed and Sealed this

Second Day of October, 2007

A handwritten signature in black ink, appearing to read "Jon W. Dudas". The signature is written in a cursive style with a large, stylized "J" and "W".

JON W. DUDAS
Director of the United States Patent and Trademark Office
